UNITED STATES PATENT OFFICE

JAMES EDWIN ELLOR, OF DERBY, ENGLAND, ASSIGNOR TO ROLLS ROYCE LIMITED, OF DERBY, ENGLAND

CENTRIFUGAL STEAM SEPARATOR

Application filed April 1, 1929, Serial No. 351,724, and in Great Britain March 8, 1928.

This invention has reference to the separating of steam from water. It is specially useful in connection with evaporative cooling systems, commonly used in connection with 5 internal combustion engines, and as forming part of the system.

In connection with various devices, including evaporative cooling systems, hot water at or approaching boiling point and steam 10 are frequently emitted from a chamber such as the cylinder water jacket of a water cooled engine, more or less intermixed, and for the purpose of condensing the steam and returning the water including the condensate to the chamber or jacket it is desirable to 15 separate the steam from the water.

In connection with cooling systems of water cooled internal combustion engines the hot water apart from the escaping steam has 20 a considerable vapour pressure, that is to say, there is a quantity of water which is only held from becoming steam by the pressure of environment water, and hence when the water is brought within the action of a pump 25 a quantity will frequently (owing to the vacuum produced) flash into steam with the result that steam bubbles are injected into the hot water jacket and localized heating results.

30 The object of this invention is to separate the steam (including water on the point of escaping as steam) from the body of water, so as to ensure that water, free from steam, shall be returned to the chamber or jacket.

35 According to this invention I construct a cooling system comprising in combination a centrifugal device, through which the water and steam issuing from the chamber or jacket passes, whereby the water is thrown to the 40 periphery of a revolving chamber while the steam is allowed to escape through a separate conduit.

45 Preferably the form of device which I adopt is one in which the water when thrown to the periphery of a chamber seals the outlet by which it escapes therefrom, against the passage of steam which perforce escapes by the provided conduit.

50 The revolving chamber may be caused to revolve either by the force of the water enter-

ring the same or by being driven from the engine or from other source of power and it may be used as a pump for causing the water to circulate in the water cooling system. The water and steam may conveniently be introduced into the apparatus by means of a volute chamber, this construction having the advantage that the water tends to collect around the outer edge of the volute assisting thereby in its separation from the steam when it reaches the revolving chamber.

In the accompanying drawings an example of this invention is illustrated.

Fig. 1 is a diagrammatic representation of an engine and radiator in which the separator also performs the function of the circulating pump. Fig. 2 is a similar diagram showing an arrangement where a separate circulating pump is used and the rotor of the separator is either driven from the engine or is self-driving. Fig. 3 is a sectional elevation of a separator made according to this invention. Fig. 4 is a section of Fig. 3 on the line 2-2 of Fig. 3.

Referring to Fig. 1, *a* is the water jacket of the cylinders of an engine, *b* is the radiator and *c* the separator made in accordance with this invention. Referring to Figure 2, *a* is the water jacket, *b* the radiator, *c* the separator made in accordance with this invention and *d* a circulating pump. In both the line of travel of the water and condensate is indicated by the short arrows and that of separated steam by long arrows.

Referring to Figures 3 and 4 the fixed part 55 of the apparatus consists of three castings *e*, *f* and *g*.

The casting *e* consists of a circular vessel with a volute passage way *e*¹ issuing from its base and a central cylindrical projection *e*².

The casting *f* is an inverted funnel shaped member with a truncated stem.

The casting *g* consists of a central chimney or shaft *g*¹, a passage way *g*² encircling the shaft or chimney forming a volute pathway through which water and steam is introduced into the apparatus.

h is a basin shaped member having an upstanding pillar having a vertical hole therethrough in its centre, and with an internal

thread around the rim and h^1 is an annular member with an external thread engaging the thread on the member h for the purpose of forming an inturned lip to such member.

5 The member h is constructed with radial blades h^2 shaped to give a narrow clearance between such blades on the one hand and the shaft or chimney g^1 and the funnel shaped member f on the other hand. The blades are 10 not necessarily respectively in one plane. They might for example be curved.

i is a spindle rotating in a flanged bearing bush i^1 formed with a shoulder i^2 and with a threaded end to engage the nut i^3 .

15 The apparatus functions as follows:—

With apparatus as described water and steam coming down the upper volute passage and moving tangentially into the basin shaped member h would cause such member 20 to rotate. But apart from such rotation the basin shaped member can be rotated through the instrumentality of the spindle i .

In either case the water is thrown to the periphery of the basin shaped member while 25 the steam collects in the centre, and as the water cannot escape until it reaches the upper edge of the member h the water forms a seal preventing any steam from escaping between the basin shaped member h and the 30 funnel shaped member f . The water escaping overflows the member h and passes down the volute passage way e^1 while all steam separated passes up through the chimney g^1 and thence to the radiator.

35 What I claim is:—

1. An apparatus for the separation of mixed water and steam, comprising a casing, a rotary basin in said casing, spaced therefrom and provided with radial blades, a 40 chimney rising from said basin for the escape therefrom of separated steam, a volute conduit leading to said basin for the passage of mixed water and steam, and an outlet conduit for the water from said basin, located 45 below the latter, the basin having a contracted outlet, at its upper edge to form a water seal, and constructed and adapted to cause the water to escape therefrom by overflowing the edge thereof.

50 2. An apparatus according to claim 1, in which the edge of the basin is formed with an inturned flange, and the inlet conduit formed with a flaring flange which is overlapped by the basin flange and contracts from 55 the basin.

In testimony whereof I have hereunto affixed my signature.

JAMES EDWIN ELLOR.
